UNITED STATES PATENT OFFICE.

PETER H. FERRIER, JR., OF CHICAGO, ILLINOIS.

BOILER.

1,416,805.

Specification of Letters Patent. Patented May 23, 1922.

Application filed October 31, 1918. Serial No. 260,503.

To all whom it may concern:

Be it known that I, PETER H. FERRIER, Jr., a citizen of the United States, residing at Chicago, in the county of Cook and State 5 of Illinois, have invented certain new and useful Improvements in a Boiler, of which the following is a specification.

This invention relates to boilers, and an object of the invention is to provide a boiler 10 construction wherein the greater or major portion of the heat from the product of combustion or gases from the fire box will be utilized in heating the water and creating heat, resulting in a material reducing 15 of the temperature of the gases upon their exhaust from the stack of the boiler.

Another object of this invention is to provide a boiler construction as specified, wherein 20 water heads are positioned both in the front and rear of the fire box and with which water heads tubes communicate which tubes also have communication with the main steam, and water chamber of the boiler, causing a circulation of the water through 25 the tubes, about which the exhaust gases pass and further to provide a plurality of baffles in the space between the fire box and stack for causing the gases of combustion to travel in a sinuous path about certain of the tubes, 30 causing a greater contact between the gases and the tubes and resulting in a maximum heating efficiency of the boiler structure and further to construct said baffles to permit them to retain a head of water therein 35 which will also be heated by the gases engaging against the said baffles.

Other objects of the invention will appear in the following detailed description taken in connection with the accompanying drawings, 40 forming a part of this specification, and in which drawings:

Figure 1 is a longitudinal section through the improved boiler.

Figure 2 is a section taken on the line 45 2-2 of Figure 1.

Figure 3 is a cross section taken on the line 3-3 of Figure 1, and

Figure 4 is a longitudinal section through the boiler showing the same adapted for use 50 upon a locomotive.

Referring more particularly to the drawings, 1 indicates the fire box of the boiler construction which has positioned therein a grate 2 of the usual construction, through 55 which air or draft is drawn for passing up-

wardly through the fuel indicated at 3 within the fire box. The walls, of the fire box are hollow being formed of spaced sheets of metal 4 and 5 which are connected by suitable stays 6 so as to provide a strong construction. The spaces between the sheets 60 4 and 5 of the walls of the fire box have communication with the main steam and water chamber 7 of the boiler, as clearly shown in Figures 1 and 2 of the drawings. 65 This main steam and water chamber 7 of the boiler is formed in the usual manner of sheet metal and it has hollow wall constructions 8 and 9 connected thereto, the lower ends of which are connected to a bottom 70 plate 10 to form a space or guideway for the gases of combustion from the fire box 1 to the stack 11 of the boiler.

The innermost wall 12 of the fire box construction is provided with an opening 13 75 therein which has communication with the space between the walls 8 and 9, allowing the draft to pass upwardly through the space 14 beneath the grate 2, through the grate fire box 1, opening 13 and outwardly 80 through the stack 11. A plurality of tubes 15 extend vertically through the space 13 having communications at their lower ends with the interior of the wall 12 and at their upper ends with the depending portions of 85 the chambers 7 allowing the circulation of the water through the wall 12 and tubes 15 into the chamber 7. A plurality of baffle plates 16, 17, 18, and 19 extend downwardly within the space 20, between the opening 90 13 and the stack 11. These baffles are hollow, and adapted to contain water, having communication at their upper edges with the chamber 7. The lower edge of the baffles 16, 17 and 18 engage the upper surfaces of 95 tubes or pipes 21 which extend longitudinally through the space 20. The lower end of the tubes 21 has communication with the interior of the fire arch or inner wall 12 of the fire box while their upper ends have 100 communication with the lower portion of the baffle 19. This baffle 19 inclines toward the forward or outer end of the boiler or toward the inlet end of the stack 11, and a baffle plate or guide plate 22 is positioned 105 within the chamber 7, extending upwardly and inclining slightly to the rear of the boiler from the rearmost edge of the baffle 19 forming a guide for the water of higher temperature passing upwardly through the 110

baffle 19. The baffles 16, 17, 18 and 19 also have communication with the side walls of the space or passage way 20.

A plurality of baffles 23, 24 and 25 are 5 positioned within the space 20 below the pipe or tube 21 and they are disposed staggeredly with the baffles 16, 17, 18 and 19 so as to cause the gases or products of combustion from the fire box 1 to travel in a sinuous path as indicated by the arrows in Figure 1 from the opening 13 to the inlet or the stack 11, resulting in a greater surface contact between the gases and the tubes or pipes 21 and also between the gases and the 10 baffles, resulting in the utilizing of the major portion of the heat of the gases for heating the water within the pipes or tubes and the baffles, consequently heating the water to a higher temperature with the same 15 amount of heat than could be done with the ordinary straight tube boiler through which tube the heated gases pass in a straight line or path.

The bottom 10 of the compartment or 20 space 20 is made up of a plurality of sections 26 and 27. The sections 27 are rigidly attached to the baffles 23, 24, and 25, while the sections 26 which are much larger than the sections 27 are hingedly connected to the 25 respective sections 27 as shown at 28. Suitable catch structures 29 are carried by the free edges of the hinged sections 26 of the lower wall 10 to hold these sections in closed position and to permit their opening 30 to gain access to the interior of the compartment 20.

From the foregoing description, taken in connection with the drawings, it will be apparent that a boiler construction has been 40 provided which presents a maximum surface area of the water containing portions thereof, for engagement by the gases or products of combustion created within the fire box, resulting in the heating of the water 45 to a maximum temperature upon the utilization of a minimum quantity of fuel.

In Figure 4 of the drawings, which shows a slight modification of the boiler construction, it being modified for application to a locomotive engine, the main features of the 50 boiler construction are the same as those disclosed in the preferred embodiment illustrated in Figures 1 to 3 inclusive it differing therefrom only in the construction of the fire box and ash pit, wherein the walls 55 of the fire box extend only to the grate, and not to enclose the ash pit as shown in Figures 1 to 3 inclusive.

In the modified form of boiler, the bottom 60 10^a of the compartment 20^a is made up of a plurality of sections 30, which are connected by means of suitable catch structures 31 at each edge thereof to the rigid portion 32 of the lower wall, and not hinged at 65 one edge as shown in the preferred embodi-

ment, and the boiler is shaped to conform to the general outline of locomotive boilers.

Changes in details may be made without departing from the spirit of this invention, 70 but;

I claim:

1. In a boiler, the combination, of a firebox having hollow water containing walls, a main water and steam chamber, a stack, an enclosed passage way communicating with 75 said stack and fire-box, and a plurality of water conducting tubes positioned within said enclosed passage and having direct communication with the interior of one wall of the fire-box and with said main water 80 and steam chamber, and a plurality of hollow baffles extending into said enclosed passage and having communication with the interior of said main water and steam chamber, said baffles arranged in staggered relation to guide the combustion gases in a sinuous path from the fire-box to said stack, the inner wall of said fire-box provided with an opening having communication with said enclosed passage, and a plurality of vertical 90 tubes extending across said opening and having communication with the interior of the main water and steam chamber and the interior of the inner wall of the fire-box.

2. In a boiler, the combination, of a firebox, a main water and steam chamber, the walls of said fire box being hollow and adapted to contain water and having communication with said chamber, a stack, an enclosed space between said stack and said 100 fire box for guiding the combustion gases from the fire box to the stack, a plurality of staggeredly disposed baffles extending into said space for guiding the combustion gases in a sinuous path therethrough, said baffles 105 being hollow and adapted to contain water and having communication with said chamber, and a plurality of water carrying tubes extending longitudinally through said space, said tubes having direct communication at 110 one end with the interior of one wall of the fire box and at the other end with the interior of the baffle plates farthest from the fire box, the inner wall of said fire box provided with an opening 115 to permit the passage of the combustion gases therethrough into said space, and a plurality of vertical tubes extending through said opening and having communication with the interior of the inner wall of the 120 fire box and with said chamber.

3. In a boiler, the combination, of a fire box, a main water and steam chamber, the walls of said fire box being hollow and adapted to contain water and having communication with said chamber, a stack, an enclosed space between said stack and said fire box for guiding the combustion gases from the fire box to the stack, a plurality of 125 staggeredly disposed baffles extending into 130

said space for guiding the combustion gases in a sinuous path therethrough, said baffles being hollow and adapted to contain water and having communication with said chamber, and a plurality of water carrying tubes extending longitudinally through said space, said tubes having direct communication at one end with the interior of one wall of the fire-box and at the other end with the interior of the baffle plates farthest from the fire box, the inner wall of said fire box provided with an opening to permit the passage of the combustion gases therethrough into said space, and a plurality of vertical tubes extending through said opening and having communication with the interior of the inner wall of the fire box and with said chamber, the lower wall of said enclosed space including a plurality of movable sections adapted to be opened to permit access to the space, and means for holding said movable sections closed.

PETER H. FERRIER, JR.
